DEVICE FOR RETRACTING SKIN

Adolph M. Brown, Chicago, Ill.

Application October 6, 1949, Serial No. 119,970

4 Claims. (Cl. 128—76)

1

This invention relates to a mechanical device which may be used to give the effect of a face lift, the device being removable and adjustably positioned as the occasion demands, to give a desired effect to the facial expression and appearance. The device is also capable of beneficial use in the retraction of skin from other parts of the body.

In my copending application, Serial No. 64,817, filed on December 11, 1948, description is made to a technique for the mechanical retraction of the human skin and to a device for effecting the same. It is an object of this invention to provide a new and improved skin retracting device of the type described.

Another object is to produce a skin retracting device of the type described, which is effective for drawing the skin taut over selected areas, which is very simple to operate, and which becomes substantially concealed when in position of use.

These and other objects and advantages of this invention will hereinafter appear and for purposes of illustration but not of limitation, embodiments are shown in the accompanying drawing in which,

Figure 1 is a perspective view of a human head showing devices embodying features of this invention in position of use;

Figure 2 is a perspective view from the under side of the device shown in Figure 1;

Figure 3 is an enlarged detail plan view taken from the under side of the view shown in Figure 1;

Figure 4 is a sectional elevational view of a modification of the device shown in Figure 1;

Figure 5 shows the device of Figure 1 in position of use, and

Figure 6 is a sectional elevational view taken along the lines 6—6 of Figure 4.

As shown, the device consists of a support including a pair of trough-like, elongate members 10 and 11 arranged in side by side spaced relation and joined at one of their ends by the curvilinear portion 12 to simulate a hairpin in appearance from the upper side. Instead of this arrangement, the support may constitute a relatively flat strip or plate of suitable, substantially rigid material, such as plastic, metal, or the like.

Arranged on the under side of the members are a pair of transversely disposed anchoring units 13 and 14, equipped with spurs 15 which are preferably dimensioned to engage the skin without breaking through or otherwise contacting the more sensitive inner layers of the skin. The anchoring units may be formed of metal, plastic,

2

or other resilient sheet material having an upper wall 16 by which it is secured to the supporting member, and an integrally depending portion 17 which is inclined at an acute angle and from which the spurs 15 extend. One anchoring member, such as the member 13, may be fixed to the underside of the support in the region of one end portion thereof, while the other member 14 is carried for a longitudinal sliding movement between two predetermined positions of adjustment on the under side of the support in the region of the other end. In their mounted relation, the dependent portion 17 and the spurs 15 of one anchoring unit are arranged to be inclined toward the same members of the other.

The mounting, permitting longitudinal movement of the anchoring member 14, comprises an elongate hanger rod 18, fixed within the trough portion of each elongate member 10 and 11. Slidably mounted on each rod is a sleeve 19. The upper wall 16 of the movable anchoring member 14 is fixed to the under side of the sleeves. The anchored ends of the rods 18 limit the extent of sliding movement of the sleeves and thereby pre-determine the positions of adjustment to which the anchoring member 14 may be moved.

The sleeves 19 are constantly urged in the direction toward the fixed anchoring unit 14 by resilient members such as coil springs 20 arranged on the rods between the respective sleeve and the anchored portion of the rod. If the spring 20 is an extension spring, it is disposed between the sleeve and the inner end of the rod. However, if it is a compression spring, it is disposed between the sleeve and the outer end of the rod.

The movable anchoring unit 14 is provided with an actuator by which it may be manually adjusted away from the fixed unit in opposition to the spring members to position the movable unit prior to embedding the spurs into the skin. In the illustration, the actuator constitutes a flange 21 fixed to the anchoring unit and extending upwardly between the spaced trough-like members.

In operation, the hair is combed aside to expose the skin and then the spurs of the fixed unit are embedded in the skin or in a plastic layer adhered to the skin near the crown of the head. The actuator 14 is moved in the direction away from the fixed unit 13 to tension the springs and then the spurs of the anchoring unit are embedded in the skin or its plastic layer in the near vicinity of the hair line. The energy, which has been stored in the spring members 20, constantly urges the movable unit 14 in the direction

toward the fixed unit 13, as guided by the support, thereby to retract loose skin from the face or the like, as illustrated in Figure 5.

To aid in the concealment of the device when in position of use, it is expedient to fix a hairpin 22 or the like in spaced apart relation with the upper wall of the support. The hairpin functions in this manner to fix the hair in a desired manner over the unit. As illustrated, the hairpin 22 may be secured at one end to a corresponding end of the support, such that its arms more or less coincide with the trough-like members of the support. Alternatively, the hairpin may be secured in any other desired manner, such as by pivoting the end upon a suitable extension 23 on the support 10.

Instead of having just one of the anchoring units fixed or movable with respect to the support, both of the units 13 and 14 may be mounted for longitudinal adjustment in a similar manner to provide for a greater displacement or else to secure equivalent displacement with a device having less overall dimension.

Some advantage is gained by the resilient arrangement of the members 16, 17, and 15, which constitute the anchoring unit, but it will be understood that the spurs may depend in angular relation from rigid cross members. Although it is best to hold the length of the spurs to less than 0.025 inch, greater lengths may be used, particularly if a coating is applied to the skin and the length of the spurs may be increased by amounts in accordance with the angular relation of the spur and the corresponding normal thickness of the skin. In the absence of a provided anchoring film, spurs dimensioned to about 0.015 inch in effective length and about 0.005 in width are to be preferred because then the spur merely engages the keratin or horny layer of the skin, which is insensitive. When so dimensioned insertion is substantially painless and there is little, if any, possibility of piercing a blood vessel.

It will be understood that numerous changes may be made in the details of construction, arrangement and operation, without departing from the spirit of this invention, especially as defined in the following claims.

What is claimed is:

1. A retractor for human skin comprising an elongate support, a longitudinally disposed hanger bar on the underside of the support, a pair of skin anchoring members mounted in longitudinal spaced apart relation on the hanger bar, at least one of said anchoring members being mounted for longitudinal sliding movement between two positions of adjustment, spurs depending from each of said anchoring members in inclined relation toward the other, a compression spring about the hanger bar disposed between the movable member and the outer end of the bar constantly to urge the movable anchoring members toward each other, and means for manually actuating the movable member away from the other.

2. A retractor for human skin comprising an elongate support, a longitudinally disposed hanger bar on the underside of the support, a pair of skin anchoring members mounted in longitudinally spaced apart relation on the hanger bar, at least one of said anchoring members being mounted for longitudinal sliding movement between two positions of adjustment, spurs depending from each of said anchoring members in inclined relation toward the other, a tension spring about the hanger bar disposed between the movable member and the inner end of the bar constantly to urge the movable anchoring members toward each other, and means for manually actuating the movable member away from the other.

3. A retractor for human skin comprising an elongate support, a longitudinally disposed hanger bar on the underside of the support, a pair of skin anchoring members mounted in longitudinally spaced apart relation on the hanger bar with at least one of said members being longitudinally slidable between two positions of adjustment, spurs depending from the anchoring member dimensioned to be of a length less than the thickness of the horny layer of the skin and in inclined relation towards each other, means constantly urging the movable anchoring members toward each other, and means for manually actuating the movable member in the direction away from the other.

4. A retractor for human skin comprising a trough shaped supporting arm in side by side spaced relation, an anchoring member fixed to the underside at one end of said trough shaped arms, a rod carried in spaced parallel relation on the underside of each trough shaped arm in the end portion opposite the fixed anchoring member, a sleeve slidable on each rod, another anchoring member fixed to said sleeves permitting sliding movement thereof toward and away from the fixed anchoring member, a coil spring on each of said rods constantly urging said sleeves toward the fixed anchoring member, and means on said movable anchoring member for actuating same in the direction away from the fixed anchoring member.
